UNITED STATES PATENT OFFICE.

WILLIAM N. BARR, OF RICHMOND, INDIANA.

IMPROVEMENT IN CANE-STRIPPERS.

Specification forming part of Letters Patent No. **58,049**, dated September 18, 1866.

To all whom it may concern:

Be it known that I, W. N. BARR, of Richmond, in the county of Wayne and State of Indiana, have invented a new and useful Improvement in Cane-Leaf Strippers; and I do hereby declare that the following is a full, clear, and exact description of the same, reference being had to the accompanying drawings, forming a part of this specification, in which—

Figure 1 is a side elevation, with one of the sides or corners removed to show the working parts. Fig. 2 is a horizontal section of same through the line *x x*.

Similar letters of reference indicate corresponding parts in both figures.

This invention consists in a novel arrangement and combination of stripping-blades, springs, and guides, whereby a greater number may be arranged in one frame, and a less number of springs are required to operate the same number of blades or strippers than in any machine heretofore constructed.

To enable others to construct my invention, and apply it to practical use, I will proceed to describe it, having reference to the drawings.

A is a frame, of wood or other material, containing within it a series of strippers, *B*, *C*, *D*, and *E*, four being represented in the drawings. Each of these sets of strippers is made up of three yielding cutting blades or edges and one stationary one. Two of the yielding blades, *a b*, of each set move outwardly from the center in a horizontal direction, and the third yielding blade, *c*, moves in a direction up or down at right angles to the blades *a* and *b*, and the stationary blade *d* in all cases is fixed near the inner edge of the frame, as shown in Fig. 1 of the drawings.

The inner opposite edge of the blades or cutting-edges *a b c d* are concave, or curved to such an extent that they form, when opened to their fullest capacity, a complete circle, or an approximation thereto when a less degree of opening is made. Each one of the blades *a*, *b*, and *c* is placed between two grooved parallel guide-pieces, *f' f'*, *h h'*, and *h' h'*, and is rigidly attached to blocks at its rear portion or side, against the outer edge of which the springs *F*, *G*, and *H* exert a pressure, always keeping the cutting blades or edges

up to their work, and causing them to fit snugly the increasing or decreasing thickness of the cane, and insuring the removal of the leaf and fodder from the entire length and surface of the cane.

It will be seen that in the arrangement of strippers and springs shown in the drawings there are four sets of strippers operated upon by eight springs, the four vertically-moving blades *c* being kept in their position by the two springs *F*, and each pair of horizontally-moving blades *b b* of the upper and lower sets is operated upon by the single spring *G*. In this arrangement there is great compactness secured, and the parts are less in number than those in machines heretofore constructed.

To prevent the longer springs *F* from bulging or buckling to either side, a guide-piece, *f*, is placed on the inside of the slides *f'* and on each side of the spring, which allows a free rectilinear motion of the springs, but tends to prevent or correct any liability of the spring bending in a lateral direction.

The whole of the springs, slides, and cutting blades or edges may be worked without being boxed in; or, to prevent foreign matter from becoming mixed in with the working parts, a cover, *J*, may be attached to the frame on each side, with apertures *jj* facing the opening to and exit from the cutting-edges.

When the cane is introduced into or between the cutting blades, the springs cause them to hug closely the surface of the cane, and strip or scrape the leaves therefrom, and the springs give or yield as the cane becomes thicker, still exerting pressure sufficient for the blades to do their work.

The red outlines shown on one of the sets of strippers in Fig. 1 show their position when open to their fullest extent, forming a complete circular opening equal in diameter to the thickness of the largest cane-stalk which may be required to pass through them.

The frame, containing any desired number of these strippers, can be arranged conveniently in connection with any of the known constructions of cane-mills, and are to be fed by hand, the roller of the mill drawing the cane through the strippers, removing the leaves, and expressing the juice at the same operation, and

the fodder or leaves stripped from the cane are left in one spot, convenient to be removed without unnecessary trouble.

I do not claim the use of two pairs of blades, one pair set back of the other, as they have been used prior to my invention. Neither do I claim the springs acting against the blades; but

What I do claim as my invention, and desire to secure by Letters Patent, is—

1. The combination of several sets of strippers in one frame, when constructed, arranged,

and operating in such manner, substantially as herein described, that one spring acts upon two stripping edges or cutters.

2. The arrangement of the parallel guide-pieces $f' h h'$, in combination with strippers B C D E and springs F G H, all constructed and operating substantially in the manner set forth.

WILLIAM N. BARR.
